UNITED STATES PATENT OFFICE.

CHARLES GABEL, OF PHILADELPHIA, PENNSYLVANIA.

DESIGN FOR A SHOE-FASTENING HOOK.

SPECIFICATION forming part of Design No. 32,249, dated February 20, 1900.

Application filed December 30, 1899. Serial No. 742,167. Term of patent 7 years.

To all whom it may concern:

Be it known that I, CHARLES GABEL, a citizen of the United States, residing at Philadelphia, county of Philadelphia, and State of Pennsylvania, have invented and produced a new and original Design for Shoe-Fastening Hooks, of which the following is a specification, reference being had to the accompanying drawings, forming part thereof.

Figure 1 is a front view, in elevation, of a shoe-fastening hook, showing my new design.

Fig. 2 is a side view. Fig. 3 is a plan view.

As shown in the drawings, the leading and material feature of my design consists of a hollow cylindrical piece of metal 1, having slits 2 at one end and a circular flange 3 at

the other. Extending upwardly and at an incline to the flange 3 is the arm 4. This arm 4 is bent at point 5 so as to form the member 6, which extends parallel to the plane of the flange 3, the upper surface of said member being concave and the lower surface convex.

Having thus described my invention, what I claim as new, and desire to secure by Letters Patent, is—

The design for a shoe-fastening hook as herein shown and described.

CHARLES GABEL.
